CLAIM

The ornamental design for laparoscopic surgical forceps as shown and described.

DESCRIPTION

1. Laparoscopic surgical forceps

Figure 1.1 is a perspective view of a laparoscopic surgical forceps;

Figure 1.2 is a perspective view thereof;

Figure 1.3 is a front view thereof;

Figure 1.4 is a back view thereof;

Figure 1.5 is a top view thereof;

Figure 1.6 is a bottom view thereof;

Figure 1.7 is a left view thereof; and

Figure 1.8 is a right view thereof.

(Continued)

The broken lines shown in Figures **1.1-1.4** and Figures **1.6-1.8** illustrate portions of the laparoscopic surgical forceps that form no part of the claimed design.
